[57] ABSTRACT

An improved glow-tube for X-ray spectrometry with directly excited samples, characterized by the positioning of a cold cathode, grid-shaped anode and an opening leading into the spectrometer chamber along the axis of the tube casing.

This glow-tube is used for X-ray spectrometric analysis and for structural analysis by diffraction or scattering.

6 Claims, 4 Drawing Figures

Fig. 1Fig. 2Fig. 3Fig. 4## GLOW-TUBE FOR X-RAY SPECTROMETRY WITH DIRECTLY EXCITED SAMPLES

This invention concerns an improved glow-tube, namely a device in which electrons are emitted in a gaseous atmosphere, for example for X-ray spectrometry with directly excited samples.

Tubes used for X-ray spectrometry include ones which operate in a deep vacuum, of about 10^{-5} mm Hg, and gas-filled tubes in which the pressure is about 10^{-1} to 10^{-3} mm Hg.

Vacuum tubes with a heated filament require a deep-vacuum installation, and emitting efficiency is low, because of the electrical energy expended in detaching the electrons from the filament. These fluorescent tubes are either sealed, with a slit, or can be dismantled to allow the sample to be inserted into the vacuum chamber. In both forms, there are disadvantages: the presence of the slit prevents the passage of retrodiffused electrons and soft X-photons with a long wavelength, needed to analyse elements with low atomic weight, while the need to place the sample in a vacuum enclosure means that only materials which will not produce degassing can be analysed. The sample, acting as anode, is exposed to intense bombardment by electrons, and can begin to melt, altering its surface composition.

There are also glow-tubes with a cold cathode, emitting a mixture of electrons and hard X-rays, and with no slit, which operate in a partial vacuum of 10^{-1} to 10^{-3} mm Hg, comparable to the vacuum prevailing in a spectrometry chamber. Exciting of the sample comes from a mixed source, since it receives a simultaneous beam of X-rays and electrons retrodiffused by the anode. During this retrodiffusion, ions are removed from the anode metal and deposited on the sample. This metal-coating effect is a disadvantage, creating a film which absorbs the X-rays emitted by the sample, and distorting the results of spectrometric analysis. In addition, at short wavelengths and large amounts of energy transmitted to the sample and needed to excite its characteristic lines could damage substances affected by heat.

The present invention concerns a glow-tube without a slit, which overcomes these drawbacks, emitting electrons directly, and with high efficiency. More specifically, it concerns a tube containing a cathode consisting of a metal disc, and a grid-shaped anode, both electrodes being located in the axis of the tube, with an opening on the same axis behind the anode, through which the electron beam is propagated by inertia, in the direction of the target.

The tube defined in this invention allows a sample to be excited directly, by direct emission of electrons, without any photons. The energy spectrum of direct, non-retrodiffused electrons is narrower than for retrodiffused electrons, so that energy is saved, since the flux needed to excite any line in the sample is much smaller. This ensures much higher emission efficiency, and prevents damage to the sample from heat. Furthermore, the anode is in the form of a grid, so that the sample is not exposed to any direct trajectory starting at the wires of the anode grid receiving the electron impacts. This means that the sample will receive very few anodic ions, and parasitic metallization will be prevented; in addition, the sample no longer diffuses the characteristic lines of the anode metal, which can interfere in the

analysis of certain elements. The tube described in the invention ensures high emission efficiency, up to 80 %, in contrast to conventional fluorescent tubes (the ratio of energy absorbed to energy emitted is approximately 10^{-4}). Compared with existing direct-emission tubes, it offers many advantages, operating without a deep vacuum, in a partial vacuum of approximately 10^{-1} to 10^{-3} mm Hg; and since the sample does not form part of the electronic optical system, it need not be a conductor.

The use of a grid-shaped anode offers many advantages. Its role is to attract the electrons in the direction of the tube-casing axis, and allow the electron beam to pass through the grid without loss of energy. The electrical field set up between the cathode and anode results only from the potential between them and, in the absence of any conducting body in the space through which this beam passes, radiation is perfectly rectilinear and trajectories are parallel. This means that the surface even of a large sample is subjected to uniform radiation, preventing localized temperature rises that could damage the surface. The electrons are propagated in a parallel beam, so that their velocities are not subject to localized variations. Since the energy spectrum emitted is narrow, the exciting efficiency for a characteristic line remains high.

Choice of the transmission coefficient of the grid allows the intensity of the radiation flux to be controlled for a given amount of electrical energy, notably if there is a possibility of heat damaging the sample.

The following table gives experimental values for different transmission coefficients, obtained by selecting appropriate grids.

Choice of the surface-area of the grid allows it to be adapted to the size of the samples being subjected to radiation, without altering the electrical and energy characteristics of the beam emitted.

The tube described in the invention thus allows great versatility in the use of equipment, which is also dependent on a fixed energy-supply source.

Type of grid	Tube flow-rate (at 3 kV)	Intensity transmitted	Temperature of the sample
Nickel wire diam. 0.5 mm mesh area 0.3 sq. mm transmission coefficient 50 %	5mA	2.55mA	235°C
Steel wire diam. 62.5 mesh area 15 transmission coefficient 40 %	5mA	1:1 mA	100°C

Other advantages offered by this tube will be clear from the following description of a preferred embodiment thereof, with reference to the accompanying drawings, in which:

FIG. 1 is a diagrammatic view showing the relative positions of the cathode, anode, and sample;

FIG. 2 is a schematic axial sectional view taken through a tube according to the invention;

FIG. 3 is a schematic view showing a conventional glow tube with its slit transverse to the axis of the tube; and

FIG. 4 shows a tube according to the present invention attached to a base for mounting it in a spectrometer.

FIG. 1 shows, in diagrammatical form, the positioning of the electrodes inside the insulating casing 1. The cathode 2 is a disc or pellet made from metal with a high electron-emitting capacity and good resistance to ionic erosion, such as aluminium. The anode 3 is a metal grid made from rhodium, rhenium or platinum, and connected to earth. The electron beam 4 emitted by the cathode travels towards the anode, and is propagated by inertia in the direction of the sample 5 placed in its path. The X-ray beam emitted by the sample, following exciting of the characteristic lines of the elements of which it is formed, is then treated by standard spectrometric methods, using a collimator, crystal and meter, arranged as a goniometer.

FIG. 2 shows the constructional details of the tube, according to a recommended embodiment of the invention. The casing is in two parts (1a and 1b), which slide inside each other. At the end of the inner casing 1a is a cathode 2 fixed to a threaded rod 6, the length of which can be adjusted and which is held by nuts 7 in the end of the casing. The electrical connections 8 are placed inside a flexible insulating covering 9. The cathode rod may be attached to a radiator with cooling fins. The outer casing 1b has an anode 3 near the end, in the form of a grid connected with earth, with a ring 10, which holds it in a groove on the inner surface of the casing.

The outer casing has a capillary inlet pipe 11 through which an adjustable flow of gas can be fed in, and the inner casing has an outlet 12, so that pressure inside the tube can be kept constant or vary. An O-ring 13 between the two casings ensures proper sealing. The distance between the electrodes can be adjusted by sliding or screwing the two casings inside one another. This distance may be pre-set, or re-adjusted without moving the tube, using a device such as a micrometric screw. A third control electrode, such as the grid 14, held in position by the ring 15 and connected to an adjustable voltage, allows further regulation.

One of the advantages of the tube described in this invention is that it can be fitted into the circular opening provided in any standard spectrometer for the fitting of the tube. FIG. 3 shows a conventional fluores-

cent tube with the slit 16 in a transverse direction in relation to the axis of the tube 1 and its cylindrical base 17. The surface 18 provides a seal during fitting to a spectrometer.

5 The design of the tube 1 described in this invention, connected with its base 17 by means of a rod 19, as shown in FIG. 4, in a transverse direction in relation to the axis of the cylindrical base 17, allows this new tube to be fitted to existing spectrometers without any alterations to the spectrometer.

10 The tube described in the invention can be used not only for X-ray spectrometric analysis, but also for structural analysis by diffraction (lattice of a crystalline phase or the structure of a liquid) or by scattering (measurement of the dimensions of particles, mixtures, etc.).

15 What is claimed is:

1. A glow-tube for use in X-ray spectrometry with directly excited samples, said glow-tube comprising at least one elongated insulating casing having an opening in one end thereof and containing a disc-shaped cathode and a grid-shaped anode, said cathode and anode being aligned longitudinally of said casing with said anode between said cathode and opening, said tube being adapted to propagate an electron beam which passes through said opening when said cathode is connected to a high voltage source and said anode is connected to ground.

20 2. A glow-tube as defined in claim 1, in which said casing comprises two parts, one of which fits telescopically into the other, with said anode in one of said parts and said cathode in the other, while a sealing ring is positioned between said parts.

25 3. A glow-tube as defined in claim 1, comprising a capillary tube near said opening for admitting an adjustable flow of gas.

30 4. A glow-tube as defined in claim 1, carried on an arm attached to a cylindrical base, with said casing at right angles to the axis of said cylindrical base.

35 5. A glow-tube as claimed in claim 1, in which the said anode is made of a metal selected from the group consisting of rhodium, rhenium and platinum.

40 6. A glow-tube as claimed in claim 1, comprising a control electrode between said anode and cathode.
